UNITED STATES PATENT OFFICE.

CHARLES WAGNER, OF GRANTWOOD, NEW JERSEY, AND AUGUST HORMEL, OF NEW YORK, N. Y.

TRANSFER-ROLLER FOR LITHOGRAPHIC PRESSES.

1,129,435.

Specification of Letters Patent. Patented Feb. 23, 1915.

Original application filed January 15, 1914, Serial No. 812,172. Divided and this application filed May 9, 1914. Serial No. 837,375.

To all whom it may concern:

Be it known that we, CHARLES WAGNER, a citizen of the United States, residing at Grantwood, county of Bergen, and State of New Jersey, and AUGUST HORMEL, a citizen of the United States, residing at New York city, county and State of New York, have invented certain new and useful Improvements in Transfer-Rollers for Lithographic

10 Presses, of which the following is a specification.

This invention relates to a novel transfer roller for lithographic presses and more particularly to novel means for securing the 15 transfer blanket under the proper tension to the supporting drum.

This application is a division of an application for lithographic press filed by us January 15, 1914 under Serial Number 20 812,172.

In the accompanying drawing: Figure 1 is a sectional side view of a transfer roller embodying our invention; Fig. 2 a cross section on line 2—2, Fig. 1, and Fig. 3 a plan 25 of the blanket.

Our improved transfer roller comprises essentially a cylindrical body or drum 10 and a transfer blanket 11 laid around said body. For properly tensioning the blanket 30 to the drum, the latter is provided with a longitudinally extending slightly tapering surface groove 12 adapted to receive a correspondingly tapering key 13, the height of said key being considerably less than the 35 depth of groove 12. Key 13 is secured in position by means of a number of screws 14 passing loosely through corresponding perforations of the key and tapped into threaded bores 15 of drum 10. These screws 40 extend through eyelets 16 secured to blanket 11 along the overlapping edges 11^a thereof, as clearly illustrated in Figs. 1 and 2. Screws 14 alternate with dowel pins 17 projecting inwardly from key 13 and likewise 45 engaging eyelets 16 of blanket 11. Pins 17 are adapted to be freely received within corresponding sockets 18 of drum 10.

When applying a blanket 11 to drum 10, the dowel pins 17 are passed through alined 50 eyelets 16 whereupon the key 13 is inserted into groove 12, the pins 17 engaging the corresponding sockets 18 of drum 10 thereby properly centering the key. Screws 14 are finally tapped into bores 15 and are tight-

ened up to such an extent as to properly 55 tension blanket 11 around drum 10.

It will be seen that by our invention, novel and effective means are provided for properly securing a rubber or other blanket to the drum of a transfer roller while these 60 means permit at the same time a ready regulation of the tension with which the blanket is stretched around said drum.

We claim:

1. A transfer roller for lithographic 65 presses, comprising a drum provided with a longitudinally extending surface groove, a blanket encircling said drum and having overlapping perforated ends that are received within said groove, a key also accommodated within the drum-groove, the thickness of said key being considerably less than the depth of the groove, dowel pins 70 projecting inwardly from the key and passing through alined perforations of the overlapping blanket-ends, and means for forcing the key into the groove to an extent sufficient for causing a tensioning of the blanket.

2. A transfer roller for lithographic 75 presses, comprising a drum provided with a longitudinally extending surface groove, a blanket encircling said drum and having overlapping perforated ends that are received within said groove, a perforated key 80 also accommodated within the drum-groove, the thickness of said key being considerably less than the depth of the groove, dowel pins 85 projecting inwardly from the key and passing through alined perforations of the overlapping blanket-ends, and screws passing 90 through the key-perforations for drawing the key into the groove to an extent sufficient for causing a tensioning of the blanket.

3. A transfer roller for lithographic 95 presses, comprising a drum provided with a longitudinally extending surface groove, alternating sockets and threaded bores provided in the drum at the bottom of said groove, a blanket encircling said drum and having overlapping perforated ends that 100 are received within said groove, a key accommodated within the drum groove and having alternating dowel pins and perforations, said dowel pins passing through the blanket-perforations and being received 105 within the drum-sockets, and screws passing through the key-perforations and blanket-perforations and tapped into the drum-

2
bores, said screws holding the key in position and simultaneously tensioning the blanket.

4. A transfer roller for lithographic presses, comprising a drum provided with a longitudinally extending surface groove, a blanket encircling said drum and having overlapping ends that are provided with eyeleted perforations, said overlapping ends being received within the drum-groove, a key also accommodated within said groove, the thickness of said key being

considerably less than the depth of the groove, dowel pins projecting inwardly from said key and passing through alined perforations of the overlapping blanket-ends, and means for forcing the key into the groove to an extent sufficient for causing a tensioning of the blanket. 15
